(57) **CLAIM**

The ornamental design for an industrial process control transmitter puck, as shown and described.

DESCRIPTION

FIG. 1 is a perspective view of an industrial process control transmitter puck.

FIG. 2 is a right side view of the industrial process control transmitter puck.

FIG. 3 is a left side view of the industrial process control transmitter puck.

FIG. 4 is a rear elevational view of the industrial process control transmitter puck.

FIG. 5 is a front elevational view of the industrial process control transmitter puck.

FIG. 6 is a top plan view of the industrial process control transmitter puck; and,

FIG. 7 is a bottom view of the industrial process control transmitter puck.
